No. 805,089.

PATENTED NOV. 21, 1905.

E. H. NORRIS.
BLAST CHARGE.
APPLICATION FILED JUNE 17, 1905.

UNITED STATES PATENT OFFICE.

ERNEST H. NORRIS, OF CEDAR RAPIDS, IOWA.

BLAST-CHARGER.

No. 805,089.

Specification of Letters Patent.

Patented Nov. 21, 1905.

Application filed June 17, 1905. Serial No. 265,768.

To all whom it may concern:

Be it known that I, ERNEST H. NORRIS, a citizen of the United States, residing at Cedar Rapids, in the county of Linn and State of Iowa, have invented certain new and useful Improvements in Blast-Chargers, of which the following is a specification.

This invention relates to mining, and has for its object to produce a blast-charger which 10 may be conveniently filled with blasting-powder, then pushed into the blast-hole, carrying the charge to the limit of the hole, and finally withdrawn, leaving the charge in a compact mass at the inner end of the hole.

15 The invention comprises a shell or charger, a plunger adapted to traverse it from end to end, a hinged handle attached to the plunger, and a hinged rod connecting with the charger-shell and by means of which it is moved end-20 wise with respect to the plunger.

In the accompanying drawings, Figure 1 is a side view of my improved charger in the act of depositing a charge in a blast-hole. Fig. 2 is a fragmentary side view of the same, 25 extended and in position to fold for convenience in filling the charger. Fig. 3 is a similar view, partly sectional, showing the device in filling position.

In mining it is common to deposit the powder for the blast in the blast-hole by means 30 of a charger, a cylindrical flask or shell to hold powder, and attached to a handle long enough to carry it to the inner end of the hole. It is not new to joint the flask to the handle 35 so that it may be turned to a vertical position and be convenient for the miner to fill; but hitherto, so far as I am aware, no way has been provided for using a jointed plunger in the flask and means for positively stripping 40 the flask back and forth over said plunger, whereby the charge is left compactly heaped at the inner end of the blast-hole. This is the purpose of this invention to secure and by means which will now be described.

45 Referring to the drawings, A designates a blast-hole, at the inner end of which it is desired to deposit a charge of powder B. For this purpose a cylindrical receptacle C, which for convenience may be called the "flask" of 50 the charger, is provided to take the charge of powder. This, as well as all other parts of the device that may come in contact with rock, should be of material that will not strike a spark, such as zinc, copper, brass, or the like.

55 In practice this is a tube of zinc, to one open end of which is fitted a ring D, of brass. To

this ring is attached a jointed rod E, by which the flask may be pushed forward or pulled back at will.

Inside the tube or flask is a plunger F, 60 adapted to slide freely therein. In practice this is made of wood, but is rimmed with zinc G to prevent its swelling and sticking in the dampness of a mine. This plunger is secured, as by a screw H, to one end of a short section 65 of handle I, jointed by a hinge J to the long section of handle K. This allows the flask to be turned upright, as shown in Fig. 3, for convenience in filling. The handle is made of wood; but for some little distance each side 70 of the hinge it is incased in sheet-zinc L to make a smooth and uniform cylinder for a sleeve M, which may be slid over the joint when the handle is straightened, and so hold it rigidly in that position. At one side of the 75 handle screw-eyes N are inserted, and these serve as guides for the rod E. When the flask is pushed to the extreme outer position, the plunger abuts against the end ring and the joints of the rod and the handle are then 80 in line, as shown in Fig. 2, so that the flask may be turned up, as above mentioned.

In the operation of the device the miner turns it to the position shown in Fig. 3 and fills the flask. He then lifts it to the blast-hole and inserts the end of it therein. Bringing the handle then to a straightened position, with one hand he grasps both the handle and the adjacent rod and with the other he slips the sleeve over the joint, and thus makes 90 the handle rigid. He then pushes the charge back as far as it will go, and, finally, holding only the handle with one hand, he pulls back the rod with the other, which strips the flask off the charge, leaving it, still held by the 95 plunger, compactly massed at the inner end of the hole. The last operation is of course to withdraw the charger, when the same is ready for another charge by slipping back the sleeve.

100 It will be noted that when in position to push the charge back into the blast-hole the rod, though jointed, is practically as rigid as the handle, and both being grasped by the hands of the miner the flask cannot slip back over the plunger until he is ready to do so, as above stated.

Having thus described my invention, what I claim as new, and desire to secure by Letters Patent, is—

110 1. In a blast-charger, the combination of a powder-holding tube or flask, a jointed rod

attached thereto, a jointed handle, and a plunger attached thereto and adapted to slide in said flask.

2. In a blast-charger, the combination of a powder flask or tube, a plunger to slide therein, a stop to limit the movement thereof, a jointed handle attached thereto, and a jointed rod attached to the flask.

3. In a blast-charger, the combination of a powder-flask, a plunger to slide therein, a jointed handle attached thereto, a jointed rod attached to the flask, guides on the handle for said rod, and a stop to limit the movement of the plunger and bring the joints of the handle and rod into alinement.

4. In a blast-charger, the combination of a powder-flask, means for moving the same back and forth with respect to an internal plunger, a jointed handle, a plunger attached thereto,

and a sliding sleeve to slip over the joint and make the handle rigid.

5. In a blast-charger, the herein-described handle, comprising two sections, a connecting-hinge, metal casings adjacent to the hinge, and a metal sleeve to slide on said casings.

6. In a blast-charger, the combination with a suitable powder-flask and handle, of a plunger of wood, somewhat smaller than the inside of the flask, and an external ring for said plunger, formed of metal, substantially as and for the purpose set forth.

In testimony whereof I affix my signature in presence of two witnesses.

ERNEST H. NORRIS.
